The ornamental design for a gripping end of a hand-held gripping extension device, as shown and described.

DESCRIPTION

FIG. 1 is a left-side view of the design for a gripping end of a hand-held gripping extension device;

FIG. 2 is a right-side view of the design for a gripping end of a hand-held gripping extension device;

FIG. 3 is a top view of the design for a gripping end of a hand-held gripping extension device;

FIG. 4 is a bottom view of the design for a gripping end of a hand-held gripping extension device;

FIG. 5 is a front-end view of the design for a gripping end of a hand-held gripping extension device;

FIG. 6 is a back-end view of the design for a gripping end of a hand-held gripping extension device;

FIG. 7 is a front left-side perspective view of the design for a gripping end of a hand-held gripping extension device; and,

FIG. 8 is a front left-side perspective view of a second embodiment of the design for a gripping end of a hand-held gripping extension device the front right-side perspective view being a mirror image of FIG. 8.

The broken line portions of the drawings are for illustrative purposes only and form no part of the claimed design.
